[57] CLAIM

The ornamental design for a post for a bathroom fixture, as shown and described.

DESCRIPTION

FIG. 1 is a perspective view of a post for a bathroom fixture which embodies my design;

FIG. 2 is a right side-elevational view thereof;

FIG. 3 is a left side-elevational view thereof;

FIG. 4 is a top plan view thereof; the bottom plan view being a mirror image thereof;

FIG. 5 is a front-elevational view thereof; and,

FIG. 6 is a rear-elevational view thereof.

The broken line shown in FIG. 1 is for illustrative purpose only and forms no part of the claimed design.
